2 Pcs Pet Hair Remover Brush, posted at amazon.com, earliest date available Jul. 8, 2020, [online], acquired on Jul. 13, 2024, Available on internet. url:<https://www.amazon.com/Cleaning-Remover-Detailer-Furniture-Clothes/dp/B08CK659X6> (Year: 2020).*

Primary Examiner — Sheryl Lane*Assistant Examiner* — Aula Soroush(74) *Attorney, Agent, or Firm* — Daniel M. Cohn;
Howard M. Cohn(57) **CLAIM**

The ornamental design for a pet hair remover as shown and described.

DESCRIPTION

FIG. 1 is a perspective view of a pet hair remover showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is an enlarged view of the portion labeled "9" encircled in FIG. 1; and,

FIG. 10 is an enlarged view of the portion labeled "10" encircled in FIG. 8.

The dot-dash broken lines show the bounds of the enlarged portions of the pet hair remover and forms no part of the claimed design.

In the drawings, the broken lines illustrate portions of the article which form no part of the claimed design.

1 Claim, 10 Drawing Sheets(56)
